UNITED STATES PATENT OFFICE.

THOMAS C. SMITH, OF BRIDGEPORT, CONNECTICUT, ASSIGNOR TO THE UNION METALLIC CARTRIDGE COMPANY, OF SAME PLACE.

METHOD OF MAKING PARTLY-COVERED BULLETS.

SPECIFICATION forming part of Letters Patent No. 680,550, dated August 13, 1901.

Application filed May 15, 1901. Serial No. 60,303. (No specimens.)

To all whom it may concern:

Be it known that I, THOMAS C. SMITH, a citizen of the United States, residing at Bridgeport, county of Fairfield, State of Connecticut, have invented a new and useful Method 5 of Making Partly-Covered Bullets, of which the following is a specification.

My invention has for its object the production of partly-covered bullets that will fully 10 meet the requirements of use.

Heretofore, so far as I am aware, partly-covered or partly-jacketed bullets have not been used to any great extent, for the reason that it was impossible to prevent the covers 15 from stripping from the slugs when fired unless the covers extended over the forward ends of the slugs as well as over the bases thereof. Among the advantages of a short jacket or partly-covered bullet it is important to note that the lead in front of the cover 20 completely fills the grooves of the gun-barrel, thereby effectually preventing escape of gas past the bullet and insuring that the full effect of the powder charge will be utilized in 25 expelling the bullet from the gun-barrel. In other words, both the maximum range and the maximum accuracy are secured; that the shortness of the cover greatly reduces the friction upon the gun-barrel, thereby lengthening 30 the life of the barrel and insuring full range, combined with perfect accuracy, for a much longer time than is possible when full-covered bullets are used; that although the lead in front of the cover will fill the grooves 35 of the gun-barrel, and thereby secure the greatest possible accuracy, the cover will clean the barrel every time the gun is fired, thereby preventing any chance of fouling of the gun-barrel even after long continued use, 40 and, furthermore, that without lessening the range to the slightest extent or impairing the accuracy of results lacerated wounds and great shock will be produced, owing to the fact that partly-covered bullets when fired at 45 a high velocity will "mushroom," as it is called, or flatten out into a jagged mass when they strike an object that offers material resistance to their passage. In order to overcome objections to all mushroom-bullets now 50 upon the market and to combine in a single bullet the advantages of mushroom-bullets

and full-covered bullets with other advantages and without the disadvantages of ordinary mushroom-bullets and full-covered bullets, I have devised the novel method of making bullets, which I will now describe, referring to the accompanying drawings, forming part of this specification, and using reference characters to designate the several parts.

In making my novel bullets I use simply 60 an ordinary slug made of lead or a relatively soft alloy and a relatively short cover made of a hard metal or alloy, said cover being simply a cup having its upper edge crimped or turned inward, and the only apparatus required is two dies and the corresponding plungers.

Figure 1 is a vertical section of the first die with the slug therein and the cover ready for swaging to place, the corresponding plunger 70 and the ejector being in elevation; Fig. 2, a similar view of the second die, plunger, and ejector, showing the slug and cover as assembled by the first operation in position for the second operation, which completes the bullet; 75 and Fig. 3 is a section of the bullet as completed by the second operation.

10 denotes the slug, and 11 the cover, whose upper edge is crimped or turned inward, as at 12. The exact length of the cover is not 80 of the essence of my invention. I have found in practice that it is amply sufficient for the purposes of my invention if the cover extends one-fourth to one-third the height of the bullet, although it may extend one-half 85 or three-fourths its height, if preferred.

13 denotes the first die, which is provided with a socket 14, which receives both the slug and the cover, as clearly shown in Fig. 1, the slug being shown as made in the form of a 90 truncated cone at both ends and the crimped edge of the cover being placed in engagement with the inwardly-tapering surface of one end of the slug, it being most convenient in practice to make the bullets with the bases upward, as shown in the drawings. The first plunger, which I have indicated by 15, is provided on its engaging end with a seat or lug 16, the object of which is to perforate the base of the cover and drive a portion of the metal 100 of the cover into the metal of the slug. My invention is of course not limited to any spe-

cial shape for this lug. I have found in practice that the desired result is attained with perfect certainty and uniformity by making this lug in such form that its central vertical longitudinal section will be a rectangle and its central vertical transverse section a triangle.

17 denotes ejectors by which the bullets are removed from the dies after the swaging operations.

The effect of the first operation—*i. e.*, the blow of the first plunger upon the uncombined slug and cover while lying in the first die—is illustrated in connection with the second die, the partly-formed bullet in the second die being the product of the operation of the first die and plunger. It will be noted that the base of the slug has been squared up, the cover has been driven down over it, the crimped edge of the cover has been clenched—*i. e.*, turned inward and downward within the slug, so that the end of the cover is, in fact, inverted or turned in the reverse direction within the slug, thus forming an absolute lock for the cover—and the base of the cover has been perforated by the lug upon the first plunger and a portion of the metal of the cover has been driven into the metal of the slug.

30 The second operation, which is performed by the second plunger 19 upon the partly-formed bullet in the second die 18, is simply to complete the swaging operation—*i. e.*, compact the cover and the slug together. It will be obvious that the exact position of the crimped edge of the cover after being driven into the slug and of the portion of the base of the cover that has been driven into the slug will never be twice alike, and, furthermore,

that sections of the same bullet at right angles to each other will show the inturned metal of the cover in different positions. This, however, is wholly immaterial so far as the principle of my invention is concerned, the object of which is, first, to clench the edge of the cover within the slug to prevent the cover from stripping from the slug or turning thereon, and, second, to clench a portion of the metal of the base of the cover within the slug as an additional means of preventing the cover from turning on the slug.

The result of the second operation is clearly illustrated in Fig. 3.

Having thus described my invention, I claim—

1. The herein-described method of making partly-covered bullets which consists in providing a slug with a tapering end and a cover having its edge turned inward to engage the taper of the slug and then subjecting the cover and slug to the action of dies, whereby the slug is forced into the cover and the edge of the cover is turned into the slug and clenched.

2. The herein-described method of making partly-covered bullets which consists in providing a slug with a tapering end and a cover having its edge turned inward to engage the taper of the slug, then forcing the slug into the cover and clenching the edge of the cover within the slug and driving a portion of the base of the cover into the slug and clenching it therein.

In testimony whereof I affix my signature in presence of two witnesses.

THOMAS C. SMITH.
